PORTABLE AERIAL LADDER

Albert J. Kiley, Belmont, and John T. Kiley, Arlington, Mass., assignors to James A. Kiley Co., Somerville, Mass., a corporation of Massachusetts

Application November 5, 1938, Serial No. 238,956

2 Claims. (Cl. 228—6)

This invention relates to aerial ladders such as are mounted on vehicles and used in the repairing and servicing of wire and lighting equipment elevated above the highway, in tree trimming, fruit picking, and in various other connections. It has particular relation to the device of this sort illustrated in our Patent No. 2,116,470 granted May 3, 1938, in which patent is disclosed a ladder combined with a self-contained erecting, adjusting, and carrying unit which can be applied quickly and easily to the floor, deck, or body of any vehicle without the need for any permanently attached structure built onto the vehicle, and which unit can be easily and quickly removed from the vehicle when not needed, whereby the general utility of the vehicle for customary load-carrying purposes, when not in immediate use as a mobile ladder base, is not impaired.

The object of the present invention is to improve the structure of our above patent in two main particulars, the first being to provide complete control of all the manipulations of the ladder by one man while standing at a single control point within the vehicle on which the aerial ladder is mounted. Hitherto in all constructions of portable aerial ladders with which we are acquainted it has always been necessary for the operator of the ladder to get out of the vehicle and go to a point remote from the ladder-extending, tilting, and swinging controls in order to unfasten the keepers, clips, detents, or hold-downs necessarily employed to hold the more remote portions of the ladder firmly in place on its support on the vehicle during transit. The inconvenience, delay, and danger incident to this operation, especially in work on overhead wires or light servicing on heavily traveled highways, particularly where the operator has been compelled to stand at the left hand side of the vehicle in so doing, has been found in commercial experience with our device to leave room for improvement. Therefore, to improve the structure in this respect, provision has been made to enable the operator to release the ladder from the retaining clips or hold-down devices, in making it ready for use, and to re-engage the ladder with such hold-down devices subsequent to use, from the same position or location in which he stands in working the other necessary controls, which as seen in our prior patent have all been grouped together to be manipulated from a single point within the vehicle. By providing remote control for the hold-down devices for the ladder the complete

manipulation of the ladder is now made possible from within the vehicle, and by a single operator, without the need to set foot on the ground and practically without moving out of his tracks.

5 The second main particular in which it is aimed to improve the patented structure and other known portable aerial ladders relates to increasing the ease and accuracy of locating the top or other elevated portion of the extended ladder in the desired relation to the wires, lights, portions of the tree, or other elevated object to which access is desired by means of the ladder. To the best of our knowledge, no prior structure has provided an extension ladder which 10 can be accurately adjusted in three dimensions by one man when in its fully extended relation and when inclined as much as 45° to the vertical. Hitherto, it has always been necessary to retract the extensible upper section of the ladder in order to reduce the unfavorable leverage exercised by the weight of the ladder sufficiently to enable one man to lift the free end of the ladder when slanted at an angle of 45° or more to the vertical. Not only does this 15 result in loss of time and added effort in retracting and again extending the ladder, but it is frequently necessary to perform the operation several times because of the difficulty in guessing where the retracted top end of the extension 20 portion of the ladder will be when again extended after adjustment. Further, it was not always convenient or possible for the single operator, even when lowering the ladder in extended relation, to watch the course of the top end of the ladder while working the controls, a part 25 of this difficulty being the concentration incident to the heavy physical effort involved in working the angular elevation gear itself. Thus 30 it was found to be very difficult to bend over and rotate the hand wheel which in our prior patented structure revolves the jack screw in one direction to allow the ladder-supporting standard to tip to lower the ladder's free end and conversely to bring back the standard to elevate such end of the ladder, while watching the position of the top end of the ladder at all 35 times to note its position with regard to other objects. Additionally, another source of difficulty has been the relatively narrow space available between the side walls of the familiar utility bodies with which these portable aerial ladders 40 are commonly combined to form service trucks for telephone and electric companies, which want of space leaves the operator no place to 45 stand between the foot of the ladder and the 50

side-wall of the body when the ladder is swung around to extend laterally over the side of the vehicle at right angles to the vehicle's length.

In accordance with this latter phase of the invention, the improved structure provides a new and more powerful elevating gear which requires much less physical effort to operate and thus makes it possible for one man to lift the ladder in its fully extended relation, and also permits this operation to be performed while the operator stands alongside of the ladder in an erect position whence he can observe clearly and easily at all times the location of the upper extremity of the ladder; preferably, also, springs are provided to counter-balance a part of the load of the ladder which resists the lifting of the ladder into more erect relation. Additionally, these results are attained while always keeping the foot of the ladder under complete and powerful mechanical control so that it cannot get away to crush the operator between its foot and the side-wall or other part of the vehicle body.

Other aims of the invention and their manner of attainment are as will be made plain hereinafter.

An illustrative embodiment of the invention is shown in the accompanying drawings in which:

Fig. 1 is a side elevation of a motor truck with utility body and a portable aerial ladder of the type shown in the aforesaid patent installed therein, showing the devices of the invention applied thereto.

Fig. 2 is a vertical section on line 2—2 of Fig. 1 on a somewhat enlarged scale, showing the improved elevating gear and the counter-balance springs.

Fig. 3 is a plan view in section on line 3—3 of Fig. 2 showing details of the elevating gear.

Fig. 4 is a plan view on an enlarged scale of the ladder rack which extends forward over the cab of the vehicle in Fig. 1, showing the improved ladder clips and the remote controls therefor.

Fig. 5 is a side elevation of the same.

Fig. 6 is a section on line 6—6 of Fig. 4.

The motor vehicle or truck of Fig. 1 has a typical utility body, which as shown in Fig. 2 comprises a number of lockers or compartments 1 for tools and materials formed in connection with spaced vertical side walls 3 located at each longitudinal side of a floor or platform 5 to which is detachably affixed at 7 the base plate 9 of a portable aerial ladder made as shown in our prior patent. Herein, as there, the extension ladder 11 is erected from its solid-line carrying position of Fig. 1 to that indicated in dotted lines in such figure by swinging it about pivot 13 at the top of standard 15, and its foot is locked down against the inclined side of such standard by spring clamps 17 and additional safety bolts, the entire standard being allowed to tilt about a horizontal axis at 19 to lower the free extremity of the ladder, and being moved reversely to elevate such extremity of the ladder by means of a jack-screw 21 having an integral head 23 on its lower end which as before rotates freely in a bushing 25 swinging on trunnions 27 in lugs 29 fixed to the under surface of turn-table 31 on which the standard 15 is pivotally mounted. Also as before, the jack-screw passes through a pivot nut 33 swiveling on trunnions 35 in suitable bearings 37 fixed on brackets fixed within the channel of a transverse channel iron 39 forming a part of the foot of swinging standard 15.

But, in contrast to the prior structure, new and improved means is provided to drive the jack-screw in place of the hand wheel previously employed. The top end of jack-screw 21 is fitted within and pinned to one element 41 of a universal joint 43 of which the other element 45 is correspondingly affixed to a square stub-shaft 47, to the end of which is welded a square sleeve 49, in which slides freely a closely fitting square shaft 51, the upper end of which is fixed within the lower element of a second universal joint 53, of which the upper element is attached and pinned to a second stub-shaft 55 pinned within the hub of a bevel gear 57, the whole providing a flexible drive-shaft. Supporting bearings are provided for stub-shaft 55, one of these being formed through the depressed central portion of a strap 59 extending across the width of the standard 15 and attached at its extremities by bolts 61 to angle irons 63 bolted to each pair of legs of standard 15. The other bearing is formed in a strap 65 bolted to strap 59 to extend over bevel gear 57, stub-shaft 55 having a head 67 which overlies the strap 65. A small bevel pinion 69 engaging with gear 57, preferably with about a 3-to-1 ratio, is fixed on one end of a shaft 71 rotating in bearings 73 on strap 59, the other end of shaft 71 having affixed thereto a hand crank 75. A simple cylindrical or cup-shaped gear-cover (not shown) is placed over the bevel gears when in use.

Additionally, to reduce the physical effort involved in tipping the standard 15 and the erected ladder while held down thereto by clamps 17, especially when the upper section of the ladder has been fully extended, counter-balance springs in the form of contracting coil springs 76 are applied to the side of the standard 15 which is remote from pivot 19, these springs being engaged at their upper ends with lugs 78 on the sides of standard 15 and at their lower ends with hooks 80 fixed in the turntable 31. The stressing of these springs during the lowering of the top of the ladder by tilting the standard 15 about pivot 19 serves to counter-balance the increasing effective leverage of the ladder as its angle to the vertical is increased, and thus the contractive effort of these springs in aiding the subsequent erection of standard 15 by means of the jack-screw and the rest of the elevating gear keeps the effort required to return the standard and ladder to elevated position practically constant regardless of the extent to which the ladder has been slanted.

By means of the train of mechanism just described, the operator is enabled to bring back the standard 15 from slanted to erect position with the ladder clamped down in erected position thereagainst, in order to raise the free extremity of the ladder, and of course to let the standard tip over to lower the free end of the ladder, while standing fully erect and while applying his force to a hand crank that is located at or about the level of his waist, where his weight and strength can be applied most effectively for this purpose. Additionally, through the mechanical advantage conferred by the powerful crank 75 and the reduction gearing at bevel gears 57, 69, added to the power already given him by jack-screw 21, and aided by the counter-balance springs 76, he is enabled to handle the ladder and to raise and lower it with facility even though it is in fully extended relation.

The provision of the universal joint arrangement avoids the difficulty otherwise met with

in attempting to extend the jack-screw shaft upward to a level where the operator could apply his force to it without needing to bend over, while still keeping it accessible for manipulation, such difficulty being the gyration of the free end of the jack-screw shaft toward and from the lower portion of the ladder as standard 15 is tipped and subsequently erected, which gyration would otherwise bring the upper end of the jack-screw shaft, or any hand wheel or crank applied thereto, into or through the plane of the ladder, to interfere with the rungs thereof, the climbing of the ladder, and the tipping of the ladder up or down about the axis 19 with corresponding rise and fall of the foot of the ladder. Omission of rungs to avoid such interference would make the climbing and descending of the ladder more difficult and risky. By the improved arrangement, the jack-screw can be slanted to provide clearance from the rungs throughout its entire amplitude of gyration, and its upper end need not itself be accessible because the driving means for the screw continue on above it, to a height and position where easily accessible to the operator.

The telescoping joint in the drive shaft for the jack-screw solves the problem of providing a support or mounting for the gears and crank at the most convenient point, namely on the tilting standard 15, in spite of the fact that such standard changes its position as the jack-screw is rotated.

To provide for releasing and re-engaging the ladder clips or hold-downs from the position where the operator stands in working the elevating gear, these clips 77 are hinged at 79 on lugs 81 fixed on inwardly extending flanges 83 of brackets 85 welded to the depending flanges of angle irons 87 forming the horizontal side members of ladder-rack 89 which extend forward over the cab 91 of the vehicle. The horizontal flanges of angle irons 87 are cut out as indicated at 93, just to the rear of the ladder-guides 95 on the ends of such angle irons, and just forward of ladder-stop 94, to provide for the outward movement of the shanks of clips 77 which removes the horizontal flanges at the top of the clips from over the ladder. Springs 97, bolted at 99 to the outside of brackets 85, bear against the shanks of the clips in an outward direction tending always to swing the clips outwardly to free the ladder. An eye-bolt 101 is threaded through the shank of each clip 77 just above the point of engagement of spring 97 therewith, and is secured by a lock-nut; to this eye-bolt is pivotally connected a yoke 103 to which is attached a flexible cable 105 sliding through guide tubes 107 clamped at 109 and 111 to suitable frame-members of ladder-rack 89, and changing direction from an extent cross-wise of the ladder-rack to one lengthwise thereof. At their rearward ends the flexible cables 105 are fixed to a member 113 connected by link 115 and yoke 117 with an operating lever 119 pivoted at 121 on a sector 123 welded to cross member 125 at the rear end of ladder-rack 89, the sector being provided with ratchet teeth 127 along its lower edge with which engages a spring pressed pawl (not shown) released by pressure on grip 129 of operating lever 119.

With the operating lever 119 thus located within a couple of feet of the top of standard 15, an operator standing alongside standard 15 in position to turn crank 75 can easily reach up 5 to press grip 129 and thus allow springs 97 to pull operating lever 119 and cables 105 forward to effect the outward movement of ladder clips 77 which frees the ladder from the ladder-rack. With very little change of position the operator 10 can then pull down the foot of the ladder and secure it to standard 15, release foot-operated clamp 131, rotate the ladder as desired on its turn-table, re-establish the clamped relation of the turn-table by clamp 131, extend the upper 15 section of the ladder and tip the standard 15 to bring the free end of the ladder to the desired spot in space by turning crank 75. After use, a reversal of these operations returns the ladder into carrying position between guides 95 on the rack 89, whereupon a rearward pull on operating lever 119 restores the clips 77 to operative relation with the ladder to hold it tightly down in place on the rack. As is obvious, all of these operations are performed by the operator while 20 standing within the vehicle, and without occasion to descend to the ground.

While we have illustrated and described certain forms in which the invention may be embodied, we are aware that many modifications 30 may be made therein by any person skilled in the art, without departing from the scope of the invention as expressed in the claims. Therefore, we do not wish to be limited to the particular forms shown, or to the details of construction thereof, but what we do claim is:

1. In a portable aerial ladder, in combination, 35 a ladder, a turntable, a support for the ladder tilting on the turntable to tilt the ladder, controls governing the movement of the top of the ladder in vertical and horizontal directions, located at the turntable and the support thereon, a ladder rack supporting a portion of the ladder that is remote from the support, a plurality of hold-down devices on the rack located at a point remote from the support, and remote control devices for releasing and re-engaging the hold-down devices comprising a lever within reach of an operator standing at the first-named controls, and intermediate connections permitting disengagement of the hold-down devices from 40 and causing re-engagement of the hold-down devices with the ladder by movement of the lever first in one direction and then in the other.

2. In a portable aerial ladder for vehicles, in 45 combination, a ladder pivotally mounted to be mechanically raised and lowered under manual control from within the vehicle, a ladder rack, hold-down devices located at a point remote from the pivotal mounting holding the ladder down against the rack, means controlling the position of the hold-down devices, and a hand-lever within reach of an operator standing within the vehicle at the said controls for the raising and lowering, actuating the said means to cause release and re-engagement of the ladder by the hold-down devices, whereby the entire operation 50 of releasing, erecting, lowering, and again securing the ladder for transportation can be effected from a central position within the vehicle.
